(57) CLAIM

The ornamental design for the fireplace frame assembly, as shown and described.

DESCRIPTION

FIG. 1 is a front elevational view of a first embodiment of the fireplace frame assembly showing my new design.

FIG. 2 is a rear elevational view of the first embodiment.

FIG. 3 is a right-side elevational view of the first embodiment. The left-side elevational view is a mirror image of the right-side elevational view.

FIG. 4 is a top plan view of the first embodiment; and,

FIG. 5 is a bottom plan view of the first embodiment.
